J. JIRASEK

MECHANICAL BAKING OVEN

Filed June 15, 1923

Patented July 15, 1924.

1,501,456

UNITED STATES PATENT OFFICE.

JOHN JIRASEK, OF DETROIT, MICHIGAN.

MECHANICAL BAKING OVEN.

Application filed June 15, 1923. Serial No. 645,612.

To all whom it may concern:

Be it known that I, JOHN JIRASEK, a citizen of the United States of America, residing in the city of Detroit, county of

5 Wayne, State of Michigan, have invented certain new and useful Improvements in a Mechanical Baking Oven, and declare the following to be a full, clear, and exact description of the same, such as will enable 10 others skilled in the art to which it pertains to make and use the same, reference being had to the accompanying drawings, which form a part of this specification.

The object of my invention is to construct 15 a mechanical baking oven, having an internal carriage installed therein, for removing the contents of the oven without reaching into the hot compartment, thus avoiding the possibility of being burned.

20 A further object is to construct an oven carriage that may be retained within the oven, and operated by external mechanical means.

A still further object is to provide a 25 mechanical oven, equipped with a mechanical lighting and ventilating apparatus.

Another object is to construct a mechanical oven that is simple in construction, easily and efficiently operated and can be manufactured at a low cost.

The several objects are secured in their preferred form by the construction and arrangements of parts more fully hereinafter described.

35 Similar parts on all drawings are marked by similar numerals.

Fig. 1, is a front view of the mechanical oven showing the relative position of the oven carriage, mechanical ventilator and the 40 lighter.

Fig. 2, is a sectional view —A A— of Fig. 1, showing the general construction and the operating mechanism.

Fig. 3 is a sectional view —B B— of Fig. 45 1, showing the mechanical lighter as installed in connection with the oven burners.

I will now describe more fully the detailed construction of the mechanical oven, and the operating parts, referring to the drawings and the marks thereon.

The oven carriage consists of a metal frame mounted on rollers in such a manner that the carriage can be moved in and out of the oven, yet at all times to be well supported when in its extreme outer position. The metal frame supports interior shelf

slides for the adjustable baking grates, and is provided with an external operating lever for moving the carriage in and out of the oven as desired.

60 The carriage consists of two metal side frames —1—, made of flat bars, and bent, forming a quadrilateral, and connected together by the metal bars —2— and —3—, at the top and bottom of the frames. The

65 connecting bars —2— and —3— are bent at the ends thereof and riveted to the side frames —1—, forming a box like frame. Along the back portion of the bottom rail

70 of the frames —1—, are mounted the bearing rollers —4—. The rollers —4— can be made of any suitable material as metal or porcelain, and are attached to the inside walls of frames —1—, by means of pivots

75 —5—, and are free to rotate thereon. The bearing rollers are grooved around the circumference to receive the projecting edge of the track —6—. The track rail —6— is made of sheet metal, of a rectangular formation, having a short open side to receive

80 the bearing rollers, forming the bearing rail therefor, supporting and guiding the oven carriage as it is moved in and out of the oven. The rail —6— is also provided with an overhanging wall to engage the upper

85 edge of the rollers —4—, for preventing the carriage from being tilted from the track rail when moved to its outer position. The rails —6— are connected together by the cross bars —7—, riveted thereto at the ends,

90 holding the track in alignment for the engaging rollers. The cross bars are attached to the bottom of the oven by the screws

95 —8—, thus holding the track in a rigid position. Attached to the inner sides of the frames —1—, are the shelf supports —9—, formed of sheet metal, crimped in parallel

seams for forming the shelf bracket —10—. On top of any set of brackets may be inserted the oven shelf —11— for supporting

100 the contents placed therein for baking. Along the front edge of the oven, near the top, is mounted the operating shaft —12—, supported by the end bearings in the oven walls, and provided with an operating han-

105 dle —13—, attached to the outer end of the shaft, outside the oven wall. On the inside of the oven, near the side walls, and attached to the shaft —12—, are the oper-

110 ating arms —14—, extending downward to the bottom of the oven, in position to swing backward and forward with the shaft

—12—. To the lower ends of the arms —14— are attached the draw bars —15—. The outer end of the bars —15— being attached to the oven carriage frame —1—, through the brackets —16—. As the shaft —12— is rotated by the handle —13—, the arms —14— move the carriage in and out of the oven upon the supporting rollers and track. Attached to the lower rail of the side frame —1—, is a draw bracket —17—, carrying attached thereto the draw bar —18— which extends through the side wall of the oven. The outer end of the bar —18— is provided with a handle —19—. After the oven door —20— has been opened, the oven carriage may be drawn out directly by means of the draw bar —18—, instead of the operating mechanism under control of the handle —13—. A stationary handle —21— is attached to the front cross bar —3— for steadyng the carriage as it is being withdrawn from the oven, and which may also be used as an operating handle if desired. Attached to the top of the oven is a ventilating chamber formed by the horizontal wall —22— extending over the top but having an open space around the outer edge thereof. Above the oven is located the fume chamber —23—, provided with an outlet pipe —24— at the top connecting with the chimney. The fume chamber —23— is connected with the oven ventilator chamber by the opening channel —25—, allowing all of the fumes gathering from the baking materials to pass from the oven. The end of the fume chamber —23— also extends over the open grate section of the stove adjoining the oven and supported on ledge —27—, and is connected thereto by means of the opening —26—, allowing the fumes from the stove burners also to escape into the chimney. Attached to the front edge of the ledge —27—, and hinged thereto, is the fume door —28—. The door —28— may be swung back under the ledge —27—, if desired, as shown in the dotted position, and locked by the latch —29— engaging the opening —30— in the back wall of the stove, closing the port opening —26— leading to the fume chamber. When in use for drawing away the fumes from the open grates, the door —28— is opened as shown in Fig. 2, and held in position by the latch —31— engaging the rack —32—, attached to the end of the oven wall. The fume door —28— may be adjusted as desired, by engaging different notches along the rack —32—.

Attached to the gas supply pipe —33—, leading to the burners under the oven, is the mechanical lighter —34—. The lighter is supplied with two jet ports —35—, po-

sitioned at an angle with the lighter frame, and leading to the oven burners. The lighter —34— is provided with a spring button valve —36—, closing the gas from the mechanical lighter. By pressing the valve stem —36— down, the gas under pressure in the main supply pipe —33—, is forced through the gas jets —35— and flows toward the burners —37— under the oven. Above the mechanical lighter —34—, located in the front wall of the oven, is a lighting opening —38—. By placing a lighted match through the opening —38—, then operating the mechanical lighter by pressing the button valve —36—, the flame is carried to the open burner jets —37—, igniting them.

I do not wish to be confined to the exact construction and arrangement of my mechanical baking oven, as herein shown and described, but claim any form of operating oven that is substantially a substitution of parts as herein set forth.

Having fully described my mechanical baking oven what I claim as my invention and desire to secure by Letters Patent is:

1. A mechanical oven carriage adapted to installation in a baking oven, comprising a metallic box shaped frame, horizontal baking grates installed within the frame, grooved rollers mounted on each side of the carriage frame, being attached to the back half of the carriage, a C-shaped track and guard rail for each set of rollers, means for fixedly attaching said rails to the bottom of the oven, and a draw handle attached to said carriage frame for moving the carriage in and out of the oven.

2. A mechanical oven carriage adapted to installation in a baking oven, comprising a metal box shaped frame having all sides open, metallic cleats attached to the inside of the frame for supporting baking grates thereon, grooved track rollers mounted on each side of the carriage frame, said grooved rollers being placed near the bottom of the frame and near the back thereof, a C-shaped track and guard rail for each set of grooved rollers, and means for attaching said rails to the bottom of the oven and for keeping the rails in alignment, an operating shaft and handle mounted in the top section of the oven above the carriage, said shaft made to rotate in said mountings, operating arms fixedly attached to the operating shaft to rotate therewith, said arms extending near the bottom of the oven carriage, a connecting bar hinged to the lower end of each operating arm and also to a fixed pivot in the side of the oven carriage frame.

In witness whereof I sign this specification.

JOHN JIRASEK.
